UNITED STATES PATENT OFFICE.

VICTOR H. HARBERT, OF CHICAGO, ILLINOIS, ASSIGNOR TO E. PAYSON SMITH, OF CHICAGO, ILLINOIS.

BRAKE-HANGER SUPPORT.

Application filed March 18, 1927. Serial No. 176,395.

My invention relates to means for supporting brake hangers pendently from the truck frames and involves a construction adapted to the use of either a continuous link type of hanger or a U-shape type of hanger, thus permitting an interchange of hangers.

The invention involves a keeper element for the hangers or the supporting pin, when the U-shape type of hanger is employed, which, as well as the supporting pin, are so constructed as to provide non-circular or irregular formed matching surfaces or inter-engaging portions whereby rotation of the pin in the keeper element is prevented during the oscillatory or swinging movements of the hanger. That is to say, the invention contemplates means whereby all wear resulting from the oscillatory movements of the hangers and the constant vibration encountered will be taken by the keeper element in instances where the continuous link type of hanger is employed; while all wear caused by the oscillatory movements of the hanger will be confined to the contacting surfaces of the hanger and its supporting pin when the U-shape type of hanger is employed.

The objects and advantages of my invention will be readily comprehended from the detailed description of the exemplification chosen for illustration in the accompanying drawing, wherein—

Figure 1 is a side elevation of a portion of a truck frame with an extension or arm formed to receive a type of keeper element and brake hanger; the figure illustrating a U-shape type of hanger and its supporting pin; portions of the hanger being broken away.

Figure 2 is a sectional end elevation taken substantially on the line 2—2 of Figure 1.

Figure 3 is a horizontal sectional view taken on the line 3—3 of Figure 1.

Figure 4 is a detail perspective view of my improved keeper element as employed in Figure 1.

Figure 5 is a side elevation of the extension or arm of the truck frame illustrating the substitution of a continuous type of link hanger, which is partially broken away.

My invention contemplates a keeper element adapted to be inserted in a socket formed in the arm or extension 15 which is preferably formed integral with the truck frame, a portion of the latter being indicated at 16. The arm is shown disposed laterally from the in-

ner side of the truck frame, with the side of the arm disposed toward the wheels of the truck provided with a continuous flange 17 of comparative lateral width and arranged to provide an elongated rectangular pocket or 60 socket open toward the wheels of the truck. The flange or rib at one end of the pocket is shown offset to provide the extended portion 18 of the pocket or socket. The pocket or socket formed by the continuous flange 17 in 65 the particular exemplification is also shown provided with transversely disposed ribs 19 at points intermediate of the ends of the pocket or socket as seen in Figure 3.

The pocket or socket is adapted to receive 70 a keeper element 20.

The keeper element consists of an elongated plate of thickness commensurate with the vertical depth of the pocket or socket in the extension 15 and of length substantially equal 75 to the length of the main portion of said pocket or socket. The keeper element is cut away or slotted transversely adjacent to the ends to provide hanger link receiving passages 21, 21; while the parallelly disposed ends 22, 80 22 are apertured at 23 to receive the hanger supporting pin 24 whereby the U-shape link or hanger 25 is pendently supported in place. The pin 24 is adapted to pass through the upper eyeletted ends of the link hanger as 85 shown after being passed through one end of the element. The keeper element, intermediate of the transverse slots 21, 21, is provided with an upwardly curved lug 26 arranged to provide a longitudinal groove 90 adapted to receive the intermediate portion of the supporting pin 24 or intermediate part of a continuous link hanger when same is to be substituted for the U-shape hanger; the groove formed by the lug 26 being therefore 95 in alignment with the apertures 23, 23 in the end portions 22 of the keeper element. The length of the lip or lug 26 is preferably such that it will fit in between the transversely disposed ribs 19 in the pocket or socket formed 100 in the arm 15 of the truck frame.

By reason of the continuous rib or flange 17, namely by having the ends of the pocket or socket closed, it is apparent that longitudinal movement of the hanger supporting 105 pin 24 is impossible after the elements have been properly assembled in place; this being accomplished by passing the supporting pin 24 through aperture 23 in one end of the keeper plate, thence through the eyeletted 110

ends of the hanger 25 and the other end of the keeper plate. The assembled elements are then inserted into the pocket or socket formed on the vertical face of the arm or extension 15, by passing the keeper element edgewise into the pocket, and the keeper element 20 locked in place in any suitable manner, as for example by the bolt 27 which is adapted to pass through registering apertures in the upper and lower portions of the flange 17 as well as through the aperture 28 of the keeper element 20.

In practice, it has been found that the constant vibrations and oscillatory movements of the brake hangers will cause the hanger supporting pin 24 to rotate in frictional relation with the keeper element and as a result subject the latter as well as the pin to considerable wear. In order to eliminate this condition, I provide the keeper element 20 at one end with an extension or lug 29 preferably to the outer side of the keeper element, namely beyond the shearing point adjacent to the end of the pin; the lug being disposed across a portion of the aperture 23 in said end so as to leave only a segmental portion of the aperture exposed as shown in Figure 4 at the right hand end of the keeper element.

30 The supporting pin 24 is provided with a flat faced reduced extension or cut-away portion at one end as shown at 30 in order that the flat face of the extension at the end of the pin may rest on the flat face of the lug 29 while the semi-circular part of the pin extension or end passes through the semi-circular aperture in the end of the keeper element and rotation of the pin therefore made impossible. It is apparent that any suitable 35 non-circular formation at the end of the pin may be employed. The interengaging portions of the pin and lug are preferably arranged beyond the bearing points of the pin in the ends of the keeper element and therefore beyond the shearing points on the pin so that the supporting strength of the pin may not be affected. It is evident that with this construction the supporting pin can have no rotation and that all wear resulting from 40 the oscillatory movements and constant vibration of the hanger will be confined to the pin and will not be transferred to the keeper element nor to any integral portion of the truck frame and hence a great saving in time, 45 labor and expense is effected; while at the same time providing a construction which permits interchange of the different types of hangers without interfering with the necessary oscillations of the continuous link hanger when employed.

Where a substitution of the continuous type of link hanger shown at 31 in Figure 5 is desired, the supporting pin 24 is removed and the upper end of the link 31 placed into 50 the groove formed by curved lip 26 of the

keeper element and the keeper element with the link inserted into the pocket or socket formed in the arm 15 of the truck frame.

The drawing is believed to present the simplest embodiment of the invention which, however, may be modified in certain respects without departing from the spirit of the invention.

What I claim is:—

1. In a brake hanger support, a keeper element comprising a transversely slotted member to provide passages adjacent the ends for the sides of a brake hanger, the portion of the member intermediate of said slots being longitudinally grooved while the ends of the members are apertured to receive a hanger supporting pin, one end of said member having a lug disposed across a portion of the aperture in said end, and a pin, one end whereof is provided with a non-circular extension adapted to rest on said lug whereby rotation of the pin is prevented. 75

2. In a brake hanger support, a keeper element comprising an elongated plate grooved longitudinally to receive a link hanger and a hanger supporting pin, said plate being slotted adjacent to the ends transversely of the groove, a portion of the plate at the end of said groove being extended into the plane of the groove and apertured to receive said supporting pin, and a supporting pin adapted to seat in said groove and in said apertures, the outer face of said portion beyond the bearing point of the pin being provided with a non-circular extension disposed across a portion of the aperture, while one end of the pin is non-circular and is adapted to bear against said non-circular extension on the plate whereby rotation of the pin is prevented. 90

3. In a brake hanger support, a keeper element formed to provide a hanger pin receiving channel disposed lengthwise of the element, the element adjacent to the ends being slotted transversely of said channel to receive the sides of the hanger while the ends of the element are apertured, a hanger pin insertible in said channel and in said apertures and provided with an extension having a non-circular perimeter, and means at the outer end of said element beyond the shearing point adapted to match the non-circular perimeter of the pin extension whereby rotation of the pin in the element is prevented. 105

4. In a brake hanger support, a keeper plate provided on one side with a grooved extension to receive a hanger or a hanger supporting pin while the ends of the plate are disposed toward the side with said extension and in spaced relation with the extension to provide passages at both ends of the extension for the sides of the brake hanger, said ends having pin receiving openings aligned with the groove in said extension, the outer end of the opening in one of said ends being non-circular, and a hanger supporting pin 120

adapted to seat in said groove with its ends in said openings, one end of said pin being non-circular and insertible in the non-circular portion of one of the openings in the plate 5 whereby rotation of the pin is prevented.

5. In a brake hanger support, a keeper element provided intermediate of its ends with a longitudinal channel while the ends have openings therethrough, the element adjacent 10 to the ends being transversely slotted to receive the sides of a brake hanger, and a hanger supporting pin insertible in the channel and

openings in said element, the keeper element on one of its ends having an extension lapping a portion of the opening in the end of the keeper element and presenting a non-circular face, while the pin has a non-circular extended end, one face whereof matches and engages the non-circular face of the extension 15 on the keeper element for preventing rotation 20 of the pin, said matching faces being beyond the bearing point of the pin.

VICTOR H. HARBERT.
